SIDNEY O. MOUNTFORD, OF NEWARK, NEW JERSEY, ASSIGNOR TO MOUNTFORD BROS.,
OF NEWARK, NEW JERSEY.

RING GAUGE.

Application filed March 25, 1926. Serial No. 97,178.

This invention relates to a ring gauge, and it is particularly adapted for use as a finger ring gauge, altho not necessarily limited in principle thereto.

5 When used as a finger ring gauge, it has a wide field of usefulness. So far as I am aware, the usual practice is for a jeweler, in determining the size of one's finger for a ring, to try a series of rings of different 10 diameters on the person's finger, until the proper size is found. This means that a large number of ring gauges must be kept on hand, and the process of determining the proper fit is not altogether easy, to say nothing 15 of the time involved.

I am aware that adjustable finger ring gauges have been heretofore proposed but those with which I am familiar are more or less complicated, and not generally used.

20 It is therefore, the principal object of my invention to provide a ring gauge which is easily and quickly adjustable and one which registers the exact size which may be read directly from the gauge.

25 Another object of my invention is to provide a ring gauge, which is simple, cheap and easy to manufacture, and hence one that is relatively inexpensive.

These and other objects will be apparent 30 to one skilled in this particular art, after a reading of the specification taken in connection with the annexed drawing, wherein

Figure 1 is a plan view looking down on the top of the gauge.

35 Figure 2 is a side view of Figure 1.

Figure 3 is a section on the line 3—3 of Figure 1, while,

Figure 4 is a section on the line 4—4 of Figure 1.

40 Figures 3 and 4 are on an enlarged scale.

In the various views of the drawings, wherein like numbers refer to corresponding parts, 1, is a frame which is relatively stiff and which I prefer to make of suitable

45 metal, such as nickel-silver, and when made of metal, one end is formed into a ring or loop 2, through which a finger of the operator may be inserted for holding the gauge when using it. The frame 1, has its opposite edges 3 and 4 bent over forming a channel or guideway therebetween. At the same time the bent over edges 3 and 4 act to stiffen the frame.

The frame 1, is provided with a longitudinal slot 5, and the end of the frame 1, opposite

the loop 2, is provided with a support portion 6, which has a slot 7, through which passes a flexible member 8, one end of which is fastened to the portion 6, in any satisfactory manner as by the metal of the portion 6, being punched downward so as to form an eyelet, over which the end of 8 is positioned. A lip 9 of the flexible member 8 extends a short distance beyond the support portion 6 and acts to complete a relatively smooth and true ring surface, and also assists in guiding the flexible member 8 into the slot 7 of the support member 6, particularly when small ring sizes are being measured. The free end of the flexible member 8, after passing 70 through the slot 7, enters the guideway between the sides 3 and 4 of the frame 1, and this free end is attached, to an operating member 11 by means of a lug 10, thrown downward from said operating member 11, which lug 10 passes through the longitudinal slot 5. The operating member 11 has a portion 12, extending in a vertical direction and preferably the edge thereof has serrations 13, which are engaged by the operator 80 using his thumb for moving the operating member 11, back and forth on the frame 1.

In addition to the lug 10, which passes through the slot 5, I prefer to provide an indentation or projection 14, in the member 11, which indentation or projection extends into the slot 5, so as to assist in positioning the member 11 on the frame 1, and to assist in preventing any undue side motion of the member 11 on the frame. 90

A scale is provided, preferably on the frame 1, which registers quarter sizes, the full sizes and half sizes being indicated on one side, such as designated by the numbers which illustrates full sizes and the quarter sizes arranged on the opposite sides of the slot 5.

In the operation of my device the frame 1, is taken in the hands of the operator, preferably so that the middle finger passes through the loop 2, the operating member 11, is pushed to the opposite end of the frame, so that the ring formed by the flexible member 8, is at its maximum size and the member 8, then passed over the object to be measured after which the operator's thumb engaging the part 12 of the operating member 11, draws the operating member toward the loop 2, thereby pulling the flexible member 8, so as to make the ring formed 105 110

thereby conform to the object being measured. When the proper fitting is obtained the size is read from the scale on the frame.

The flexible member 8 may be made of any satisfactory material, either metal or some other substance, suitable for the purpose, but I preferably make all of the parts of metal, such as nickel-silver, and when so constructed only three parts are required; the frame 1, the flexible member 8, and the operating member 11.

It will be thus seen that I have provided a ring gauge of a very few number of parts; one that is easy to manufacture, and easy to operate, and it will also be obvious that my invention is susceptible of certain changes for example the measuring ring 8 may be somewhat narrower than the part which fits in the guideway between the side members 3 and 4, and the method of attaching the flexible member 8 to the frame 1, may be different from that illustrated. However, such changes are considered to be within the scope of my invention, and the range of the appended claims.

Having thus described my invention, what I claim is:

1. A ring gauge comprising; a one piece frame having a longitudinal slot therein, and a relatively wide guideway formed by the bent over edges of the frame and a flexible member formed ring shaped, and having one end attached to the frame, at one of its ends, and the other end of the flexible member entering the guideway closely adjacent the point where its first mentioned end is attached to the frame, and a hand operated member movably carried on only one side of said frame, and having a part extending through said slot and attached to the end of said flexible member, which is positioned in said guideway, said frame having means cooperating with said movable member to indicate the size of said ring shaped member.
2. A ring gauge comprising; a frame having a longitudinal slot therein, a longitudinal guideway and a transverse slot registering with said guideway, a flexible member formed ring shaped and having one end attached to the frame near said transverse slot and the other end passing through said slot into the guideway, a movable member carried on said frame, and means associated therewith and extending through said longitudinal slot and fastened to the end of the flexible member which is positioned in said guideway, said frame having means associated with said movable member to indicate the size of said ring shaped member.
3. A ring gauge comprising; a frame having a loop at one end to act as a holder and having its edges formed to provide a channel shape guideway on one side of the frame, said frame having its end opposite said loop offset and having a transverse slot in said

offset portion registering with said guideway, a flexible member formed ring shaped and having one end attached to the frame near said transverse slot and the other end passing through said slot into the guideway, a member movably carried on said frame and means associated therewith and extending through said longitudinal slot and fastened to the end of the flexible member which is positioned in said guideway, said frame having means cooperating with said movable member to indicate the size of said ring shaped member.

4. A ring gauge comprising; a frame having a loop at one end to act as a holder and the edges formed to provide a channel shaped longitudinal guideway, said frame having its end opposite said loop offset and a transverse slot in said offset portion registering with said guideway, a flexible member adapted to be drawn into the shape of a ring having one end fastened to said frame offset portion and the other end passing through said slot into said guideway, said flexible member having a tip extending beyond said offset frame portion for the purpose described, an operating member for the flexible member carried on the frame, means for attaching the operating member to the end of the flexible member lying in said guideway, said frame having means cooperating with said movable member to indicate the size of the ring shaped by movement of said flexible member.

5. A ring gauge comprising; a frame having means for supporting the same on a finger of the user, said frame having a guideway substantially the width of the frame, and formed by bending over the edges of the frame and an integral guide and support portion at one end, said portion having a slot therein to cooperate with said guideway, a flexible member adapted to take a cylindrical shape and having one end fastened to the frame and the other passing over said support portion and through said slot into said guideway, an operating member for the flexible member carried on the frame, means for attaching the operating member to the end of the flexible member lying in said guideway, said frame having means cooperating with said movable member to indicate the size of the ring shaped by movement of said flexible member.

6. A ring gauge comprising; a frame having means for supporting the same on a finger of the user, said frame having a guideway substantially the width of the frame, and formed between the bent over edges of the frame and an integral guide and support portion at one end, said portion having a slot therein to cooperate with said guideway, a flexible member adapted to take a cylindrical shape and having one end fastened to said support portion and extending be-

yond said support portion for the purpose described, the other end of said flexible member passing over said support portion through the slot into said guideway, said frame having a longitudinal slot therein, an operating member slideable on the frame and having a tongue extending through said longitudinal slot and fastened to said flexible member in the guideway, means for assisting in preventing said operating member from twisting on the frame, said frame having a scale cooperating with said operating member to show the size of the ring formed by the flexible member on actuation of the operating member.

7. A ring gauge composed of three parts, a frame having one end formed into a loop for handling the frame and its edges bent over to form a guideway, a flexible member 20 circularly formed and having one end fixed to an end of the frame and its other end held in said guideway and adapted to be

moved longitudinally therein, an operating member carried by the frame and attached to the movable end of said flexible member, 25 said frame preferably having a scale for indicating the size of the circular part formed by the flexible member on movement of the operating member.

8. A ring gauge comprising; a frame having a channel shaped guideway and a support portion at one end having an opening registering with the guideway, a flexible member circularly formed and having one end fastened to said support portion and its 30 free end passing through said opening into the guideway closely adjacent said fastened end, a hand operated member slidably carried on the frame and attached to the free end of said flexible member for the purpose 35 described.

In testimony whereof, I affix my signature.

SIDNEY O. MOUNTFORD.
